UNITED STATES PATENT OFFICE.

ALICE J. DAY, OF BROOKLYN, NEW YORK.

SLEEVE-FORM.

SPECIFICATION forming part of Letters Patent No. 716,199, dated December 16, 1902.

Application filed April 15, 1902. Serial No. 103,024. (No model.)

To all whom it may concern:

Be it known that I, ALICE J. DAY, a citizen of the United States, and a resident of New York, borough of Brooklyn, in the county of Kings and State of New York, have made and invented certain new and useful Improvements in a Combined Sleeve and Collar Form, of which the following is a specification.

My invention relates to an improvement in sleeve-forms, the object being to produce a device of this kind which may be employed for holding a sleeve in shape while making and trimming the same and which, combined with a shoulder and collar form, may also be utilized for retaining the sleeves and collars of garments in proper shape while not in use or on exhibition.

At the present time it is the practice of those employed in making and trimming sleeves to allow the same to lie flat, whereby they often become creased and wrinkled.

The object of my invention is to provide a device of the character above mentioned which will retain the sleeve in somewhat the shape it assumes while being worn, thereby enabling the operator to finish and trim the same far more readily and with more exactness and neatness and without in any way wrinkling or damaging the article.

With these and other ends in view the invention consists in certain novel features of construction and combinations of parts, as will be hereinafter fully described, and pointed out in the claim.

In the accompanying drawings, Figure 1 is a view in side elevation of my improved sleeve-form. Fig. 2 is a view in front elevation. Fig. 3 is a detached view of the shoulder and collar form. Fig. 4 is a detail-view showing the ends of the sections riveted together and the construction of the end through which the adjusting-tape passes. Fig. 5 is a sectional view taken on the line 5-5 of Fig. 4, and Fig. 6 is a sectional view in detail, showing the method of passing the tape through the end of one of the metallic sections.

Referring to the drawings, it will be seen that the form partakes somewhat of the shape of a sleeve—that is, circular in cross-section and decreasing in size from the shoulder toward the wrist or lower end—the form consisting of a number of circular loops placed

or arranged diagonally or at an angle with each other—as, for instance, the circular loop, consisting of the four curved metallic strips 55 or sections 6 7 8 9, is arranged diagonally to and crossed by the loop consisting of the sections 10 11 12 13, this arrangement of parts being followed throughout the entire sleeve-form, the ends of four sections meeting at a 60 common point and secured together by means of a rivet 14, as illustrated at Figs. 4 and 5, the fastening being sufficiently loose to allow of the loops being forced in a direction toward or away from each other, whereby to 65 lengthen or shorten the form. Along the under part of the form runs a tape or strip of pliable material 15 and on the outer part or side a similar tape 16, whereby the several loops may be held in any desired adjustment 70 with relation to each other, these tapes passing through slots 17, formed in the plates 18, with which one section is provided, where the four ends are riveted together at the outer and under parts of the form, this construction and arrangement of parts allowing the 75 several loops, each made up of four sections, as before described, to be drawn together and so held when the form is to be shortened and the adjusting-tapes to slide through the slot- 80 ted plates when the loops are to be separated to lengthen the form.

To the upper and larger end of the sleeve-form and to any of the desired sections may be attached the shoulder and collar form illustrated in Fig. 3, this portion of the device consisting of the several sections 19 20, riveted at their inner ends 21 and at their outer ends 22, the said sections being provided at their outer ends with the plates 23, formed with the 90 slots 24, Fig. 6, through which pass the adjusting-tapes 25, whereby the shoulder-form may be lengthened and shortened on the principle of the lazy-tongs. To the sections 27 is secured the collar-form, consisting of the sections 28, preferably made of spring metal, as are the sections of the shoulder and sleeve forms, these sections 28 being riveted at their outer ends 29 and provided with the plates 30, slotted, as in the instance before referred to, 100 through which pass the tapes 31 for increasing or decreasing the size or length of this portion of the device.

From the foregoing it will be understood

that when the combined sleeve, shoulder, and collar forms are inserted within a garment the latter may be trimmed or finished with far more readiness, neatness, and exactness than when the same is allowed to hang loose, the form being of approximately the same size as the garment-sleeve with which the same is employed. It will be further understood that the device may also be utilized to keep the garment in proper shape after completion and while the same is not in use or upon exhibition in stores, &c. Being made of tempered sheet metal, the same is inexpensive to manufacture and can be easily and readily adjusted for use by means of the adjusting-tapes.

Having fully described my invention, what

I claim as new, and desire to secure by Letters Patent, is—

A sleeve-form consisting of a number of 20 circular loops, each loop consisting of four sections, the ends of said sections being riveted together, the ends of several of said sections being provided with slotted plates, and tapes passing through said slotted plates, 25 whereby the length of said form may be adjusted, substantially as described.

Signed at New York, borough of Brooklyn, in the county of Kings and State of New York, this 11th day of April, 1902.

ALICE J. DAY.
